UNITED STATES PATENT OFFICE

2,296,076

TOELESS SPLICE BAR

David Wood, New York, N. Y.

Application November 9, 1940, Serial No. 365,050

1 Claim. (Cl. 238—222)

This invention relates to toeless splice bars for rail joints.

An object of this invention is to provide splice bars for rail joints of the character described, which shall be easy to apply, and which shall prevent bumpiness at the rail joint.

A further object of this invention is to provide a strong, rugged and durable splice joint for rails, which shall be relatively inexpensive to manufacture, easy to install, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawings, in which is shown various possible illustrative embodiments of this invention:

Fig. 1 is a top plan view of a rail joint provided with splice bars embodying the invention;

Fig. 2 is a side elevational view of the structure shown in Fig. 1;

Fig. 3 is a cross-sectional view taken on line 3—3 of Fig. 2;

Fig. 4 is a side elevational view of the splice bar removed from the rail joint;

Fig. 5 is a top plan view, similar to Fig. 1, but illustrating a modified construction; and

Fig. 6 is a side elevational view of the splice bar used in the construction illustrated in Fig. 5.

Referring now in detail to the drawings, 10 and 11 designate the meeting ends of rails spliced together by splice bars 12, embodying the invention. The rails 10 and 11 are similar and symmetrically disposed. Each has a base portion 14, a web 15 and a rail head 16. Adjacent ends of the rail heads 16 are cut away at the opposite sides of the center, as shown at 18, leaving only the center portion 19 of the rail head in alignment with the web 15. Portions 19 preferably taper toward their outer ends.

The inner ends of portions 19 and webs 15 of the rails 10 and 11 are substantially in abutment.

The splice bars 12 are similar and symmetrically disposed. Each has a bottom flange 30 contacting the upper side of the base 14, a web portion 31 extending from the portion 30, and disposed alongside of the web 15. The upper edge of web 31 contacts the underside of the rail head, as at 33.

Extending upwardly from the web 31 of the bar 12, is a portion 37 disposed within the cut-

away portions 18 of the rail heads 16. The portions 19 of the rail heads 16 are thus disposed between the portions 31 of the splice bars. The web portions 31 of the splice bars are formed with openings 40 registering with openings 41 in the webs of the rails to receive through bolts 42 for attaching the splice bars to the rails 10 and 11.

The inner surfaces of portions 37 are preferably inclined upwardly and inwardly, as shown at 46, in Fig. 3 of the drawings.

In Figs. 5 and 6, there are rails 10a and 11a. Rail 10a is of uniform cross-section throughout. Rail 11a is similar to rail 11. To attach the rails 10a and 11a, there is provided fish or splice bars 12a, similar to the bars 12, with the exception that said splice bars are provided with upward projections 37a, half the length of the projections 37, or equal substantially to the length of portion 19a of the rail head of the rail 11a.

It will be noted that portions 37 and 37a of the bars 12 and 12a have upper and outer surfaces registering with the head of the rail.

It will be furthermore noted that the projections 37 and 37a are disposed at intermediate portions of the splice bars 12 and 12a, respectively.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

In combination, two abutting rails, one of said rails having a head tapered to form a recess at each side of the rails, said recessed portion having side walls tapering toward the top of the rail, two splice members, each having a bottom flange, an upwardly extending web portion and a portion at the upper edge of the web portion intermediate the ends of the member, said intermediate portion being complementary in shape with said recessed portion, the bottom flange of each splice bar resting on the base portion of the rail and the web portion abutting the underside of the head of the rail, an intermediate portion fitting into a recess, and means for securing said splice bars to the rails.

DAVID WOOD,
